CROSS-FEED MECHANISM FOR GRINDING-MACHINES.

1,339,860.

Specification of Letters Patent.

Patented May 11, 1920.

Application filed June 27, 1917. Serial No. 177,350.

To all whom it may concern:

Be it known that we, CHARLES H. NORTON, ALBERT TURNER, and JOSEPH S. WILCOX, Jr., citizens of the United States, residing at Worcester, in the county of Worcester and State of Massachusetts, have invented a new and useful Cross-Feed Mechanism for Grinding-Machines, of which the following is a specification.

10 This invention relates to a cross feed mechanism and is particularly designed for use in a cylindrical grinding machine.

For certain types of grinding operations it is desirable to use wheels of relatively 15 soft grade in which the bond between the cutting particles gives away readily and allows dulled, useless grains to break off, thereby presenting new and sharp surfaces in constant succession, as the cutting proceeds, 20 and permitting a more rapid rate of action. However, due to the softness of the bond, if the wheel is fed toward the work too rapidly, there is a marked tendency for the fillets or corners of the wheel to break down, 25 or for the wheel to become impaired in other ways. When the feed is by hand and within the control of the operator, subject to his whims or carelessness, and is too slow at one time and then at another is too rapid to 30 make up for lost time, the net result is imperfect work or heavy wear and tear on the machine and the grinding wheel.

Furthermore, in the semi-automatically operated grinding machines heretofore 35 known, the wheel feed has been intermittent in operation, a ratchet and pawl feed being commonly used. In order to feed the wheel forward by pawl and ratchet it is necessary to move it rapidly during a portion of the 40 grinding period and too deeply into the work, causing the wheel to be subjected to the strains of heavy grinding which gradually diminishes as the material is cut away until the feed is again operated and the 45 cycle repeated.

In accordance with our invention, an absolutely uniform feed is provided during the grinding operation so that the wheel may be moved continuously at a predetermined rate and much slower than when fed intermittently to accomplish the same re-

sults. Consequently our wheel is not subjected to periodic excessive strains, tending to cause premature disintegration, and so will last longer for its work, while the 55 grinding operation proceeds smoothly and with a minimum of wear and tear on the machine.

It is therefore an object of our invention to provide a non-intermittent feeding mechanism for relative movement of grinding wheel and work which will be entirely automatic in operation and which will feed the wheel into the work at a constant uniform and predetermined rate of cutting that is 60 not subject to variation by the operator during a given grinding operation after the wheel has been brought into cutting contact with the work. At the same time the operator may decide which one of several uniform rates of speed shall be utilized, and he may manually control the mechanism to the extent of changing from one speed to another or stopping or reversing the feed, although he cannot vary the rate momentarily 70 and he cannot feed the work by hand during the grinding period, before an automatic feed stopping mechanism has been brought into action.

Our broad invention consists, therefore, 80 in the provision of an exclusively automatic cross feeding mechanism particularly adapted for cylindrical grinding machines.

In grinding operations, particularly when performed upon rough castings or forgings, 85 it is found desirable to provide three different predetermined feeds including a fast feed for bringing the wheel forward to a point adjacent the work, an intermediate feed for use in grinding off irregular projections or fins upon the forging or casting, and a comparatively slow or fine feed for use when the grinding wheel begins to cut into the solid body of the stock. Accordingly, an important feature of our invention relates to the provision of improved 95 mechanism by which a plurality of predetermined rates of cross feed may be obtained, these several rates being under the selective control of the operator. This 100 mechanism is entirely distinct from the provision commonly made for a general in-

crease or decrease in the speed of the entire cross-feeding mechanism as by a cone pulley on the driving shaft.

Another important feature of our invention relates to new and improved devices by which the cross feed may be thrown out of action at a fixed point predetermined with a very high degree of accuracy.

In the preferred form, this feature of our invention comprises a stop, a stop-engaging member mounted to permit a partial rotation, a clutch on the cross feed shaft, and positive geared connections from said clutch to said stop-engaging member. The clutch is normally held inoperative and adjustable automatic devices are provided for releasing the clutch as the wheel approaches the finish of the cut. The stop-engaging member then rotates until it engages the stop and positively holds the cross feed screw from further advance movement, this action being made possible by a friction connection between the drive shaft and the cross feed shaft.

A further feature of our invention relates to the provision of a device by which the cross feed may be readily adjusted for work of widely differing diameters, the adjustment being of an extremely simple nature.

Our invention further relates to certain arrangements and combinations of parts which will be hereinafter described and more particularly pointed out in the appended claims.

The preferred form of our invention is shown in the drawings, in which—

Figure 1 is a front elevation of a grinding machine with our improved cross feed mechanism embodied therein;

Fig. 2 is a sectional side elevation of the cross feed mechanism taken along the line 2—2 in Fig. 1;

Fig. 3 is a front elevation of the shifting mechanism through which the operator controls the changing and reversal of the feed;

Fig. 4 is a top plan view of the feed changing and reversing handles, indicating their several operative positions;

Fig. 5 is a sectional plan view taken along the line 5—5 in Fig. 3, and showing the cam and cam follower which control the slow and intermediate feeds, the parts being set for slow feed;

Fig. 6 is a view similar to Fig. 5, but showing certain additional parts of the mechanism, set for intermediate feed;

Fig. 7 is a plan view of the cam and connections which control the fast feed of the grinding wheel, the parts being shown, however, as they appear during the slow feed of the wheel;

Fig. 8 shows certain of the same parts in

the position which they assume during the intermediate feed of the grinding wheel;

Fig. 9 shows the cam and cam follower in the position to render the fast feed operative;

Fig. 10 is a vertical sectional elevation of the manually operated feed changing and reversing mechanism, taken along the line 10—10 in Figs. 4 and 11;

Fig. 11 is a plan view of the reversing mechanism, partly in section, and taken along the line 11—11 in Fig. 10;

Fig. 12 is a sectional side elevation of certain of the parts shown in Fig. 2, drawn on an enlarged scale;

Figs. 13 and 14 are face views of the two members of a clutch taken along the line 13—13 and 14—14 respectively in Fig. 12;

Fig. 15 is an enlarged side elevation, partly in section, of the device for automatically stopping the cross feed;

Fig. 16 is a front elevation of a portion of the device shown in Fig. 15, and showing particularly the means for manually adjusting the stop-engaging member;

Fig. 17 is a plan view of a portion of the mechanism through which the clutch is controlled which starts the automatic stopping device in operation;

Fig. 18 is a plan view of additional parts of the clutch control mechanism shown in Fig. 17;

Fig. 19 is a vertical sectional view of the parts shown in Fig. 18 taken substantially along the line 19—19 in said figure, and

Fig. 20 is a partial detail sectional view of the clutch-actuating sleeve.

Referring to the drawings, we have shown our improved cross feeding mechanism as applied to a cylindrical grinding machine of a common type having a frame 10 upon which a work supporting table 11 is longitudinally movable. Work driving heads 12 are longitudinally adjustable upon the table 11 and suitable provision is made for rotating the work K (Fig. 2) supported thereby. These parts constitute no part of our present invention, and may be of any usual type.

The grinding wheel W is mounted on a wheel shaft 13 rotatable in bearings 14 and 15 in a cross feed carriage 16 slidable on suitable ways, not shown, formed on the rear portion of the frame 10. The grinding wheel may be driven by a belt 17 running on a driving pulley 18 secured to the shaft 13, or other suitable driving mechanism may be utilized.

The wheel carriage 16 (Fig. 2) is provided with a depending portion 19 to which is secured a half nut 20 which co-operates with a cross screw 21 formed on a cross feed shaft 22 rotatable in a bearing 23 in the frame 10 and a bearing 24 in a frame

member 10^a. A weight 25 is attached by a cord or chain 26 to the wheel carriage 16, normally drawing the carriage to the rear and taking up all backlash between the 5 nut 20 and the feed screw 21.

A gear 27 (Fig. 12) is loosely mounted upon a sleeve 28 keyed to the shaft 22 and having an outwardly projecting flange 29 to which a ring 30 of friction material is 10 secured. The gear 27 is pressed against the friction surface or ring 30 by an outer sleeve 31 keyed to the sleeve 28, but slideable thereon and having a flange 32 with a friction ring 33 engaging the side of the gear 27 15 opposite to that engaged by the ring 30. A spring 34 encircles the sleeve 28 between the end of the sleeve 31 and a collar 35, said spring being effective to force the friction surfaces into driving engagement with 20 the sides of the gear 27. The collar 35 is threaded upon the sleeve 28 and may be longitudinally adjusted thereon to vary the pressure of the spring 34.

The gear 27 meshes with a gear 36 rotatable on a short shaft 37 fixed in a bracket 38 on the frame member 10^a. The gear 36 meshes with a wide-faced pinion 40 formed on a clutch sleeve 41 loose on an intermediate shaft 42 and provided with clutch 30 teeth upon each end thereof. The sleeve 41 is slideable on the shaft 42 by means of a yoke 43 (Fig. 7) which is manually controlled by devices to be hereinafter described. The teeth 44 at the rear end of 35 the sleeve 41 are adapted to engage similar clutch teeth 45 formed on a flanged collar 46 keyed to the intermediate shaft 42.

The shaft 42 is rotatably mounted in bearings 47 and 48 in the frame member 10^a and 40 at its forward end is provided with a bevel gear 50 meshing continuously with corresponding bevel gears 51 and 52 (Fig. 11) each freely rotatable upon a clutch shaft 53 extending longitudinally of the machine and 45 rotatable in bearings 54 and 55 (Fig. 11) and 56 (Fig. 3).

The shaft 53 is in alignment with a driving shaft 57 supported in fixed bearings 58 (Fig. 3) and 59 (Fig. 1). A cone pulley 60 may be secured to the driving shaft 57 and a belt shifting block 61 (Fig. 1) may be 50 slideably mounted upon the frame 10 for shifting a driving belt upon the cone pulley 60. The feeds of the entire cross feed 55 mechanism may thereby be increased or decreased as a related whole.

We will now describe the connections between the driving shaft 57 and the clutch shaft 53. The driving shaft 57 is provided 60 at its left-hand end, as viewed in Fig. 3, with a clutch collar 62 positioned for engagement with the teeth 63 of a slideable clutch collar 64 keyed to the clutch shaft 53. The collar 64 is controlled by a yoke 65 and other

mechanism to be described. When the collar 64 is moved to its right-hand position with its teeth 63 engaging the clutch collar 62, there is a direct drive from the shaft 57 to the shaft 53, this arrangement giving the intermediate feed shown in Fig. 6, or the 70 fast feed.

A pinion 66 (Fig. 3) is fixed to the shaft 57 and engages a gear 67 on a shaft 68 mounted in a fixed bearing 69, and having a pinion 70 engaging a gear 71 loosely 75 mounted upon the shaft 53. The gear 71 is provided with clutch teeth 72 adapted for engagement by teeth 73 upon the left-hand end of the clutch collar 64. When the clutch collar is moved to the left so that the teeth 72 and 73 are in engagement the shafts 57 and 53 are connected through the compound gears 66, 67, 70 and 71, and the slow or fine feed of the wheel carriage is thus secured.

The yoke 65 which determines the position 85 of the clutch 64 is mounted upon a rod 74 (Fig. 3) slideable in a bearing 75 and having secured to its opposite end a cam follower 76 (Fig. 6) embracing a cam 77 fixed to the lower end of an upright shaft 78 (Fig. 10) 90 rotatable in a sleeve 79 which in turn is rotatably mounted in fixed bearings 80 and 81 (Fig. 3).

A feed control handle 82 is keyed to the upper end of the shaft 78 and the hub of the 95 handle 82 is provided with three notches 83 positioned for engagement by a spring plunger 84 mounted in a fixed support 85, the plunger 84 serving to hold the handle 82 yieldingly in three different positions. When 100 the handle is in the position indicated in full lines in Fig. 4 and marked "Slow" the position of the cam follower 76 and cam 77 are as indicated in Figs. 3 and 5, the clutch 64 engaging the clutch teeth on the gear 71 105 and the drive from the shaft 57 to the shaft 53 being through the compound gearing previously described.

When the handle 82 is moved from the position marked "Slow" in Fig. 4 to that 110 marked "Intermediate" the cam follower and cam assume the relative positions shown in Fig. 6, thereby causing the clutch 64 to engage the clutch collar 62 and providing a direct drive at a higher speed from the shaft 115 57 to the shaft 53.

In order to complete the description of the means by which the several rates of feed are secured, it is necessary to further explain the driving connection between the wide-faced pinion 40 and the intermediate shaft 42 previously described.

As stated, the clutch collar 41 (Fig. 12) is provided at its rear end with clutch teeth 44 adapted for engagement with clutch teeth 125 45 on a collar 46 fixed to the shaft 42. The clutch collar 41 is also provided with clutch teeth at its forward end adapted for engage-

ment with corresponding teeth upon the hub 90 of an internal gear 91 freely rotatable about the axis of the shaft 42. An internal ring gear 92 is fixed in the frame member 5 10^a concentric with the shaft 42 and adjacent to the side of the internal gear 91. A double pinion 93 is rotatably mounted upon an eccentric sleeve 94 fixed to the shaft 42 and rotatable therewith. provided with key-ways 122 adapted to receive keys 123 (Fig. 13) pinned in corresponding key-ways in the shaft 22. A spring 124 encircles the shaft 22 and is secured thereon by a nut 125 and washer 126. The opposite end of the spring engages an internal shoulder 127 of the sleeve 121 and, when permitted to act, pushes the sleeve toward the rear or to the right in Fig. 12. Such movement of the sleeve is communicated to the gear 120 by means of a shoulder 128 on the outside of the sleeve 121.

10 A toothed ring 129 (Figs. 12 and 13) is secured to the rear face of the gear 120, the teeth thereon being irregularly spaced and being adapted to engage corresponding teeth on a flanged collar 130 (Figs. 12 and 14) keyed to the shaft 22. The ring 129 and collar 130 thus constitute a clutch which can be engaged only in a single position. A ring 132 (Figs. 12 and 13) is fastened by screws to the right-hand end of the sleeve 121 and thus provides means for causing the gear 120 to move to the left to disengage the clutch when the sleeve 121 is moved in that direction.

15 Pawls 133 (Fig. 12) are mounted in the key-ways of the sleeve 121 and are pivoted to said sleeve by pins 134. The outer ends 30 of the pawls 133 engage a grooved collar 135 slidable upon the sleeve 121 and positioned by a yoke 136 controlled by mechanism to be described. Flat springs 137 are secured in the key-ways of the shaft 22 and normally force the pawls 133 outwardly into position to engage overhanging portions of the keys 123, when the collar 135 is moved to the left (in Fig. 12) by devices to be described. When the parts are 40 in this position the pawls prevent movement of the sleeve 121 by the spring 124 to the right and therefore prevent engagement of the clutch members 129 and 130. The gear 120 is under these conditions free to rotate 45 upon the sleeve 121.

20 The gear 120 meshes with a pinion 140 (Fig. 15) rotatable upon a stud 141 fixed in the frame member 10^a. A gear 142 is secured to the pinion 140 and meshes with a 50 pinion 143 mounted on an arm 144 freely movable for a part of a revolution on the outer end of the stud 141. When the stopping device is inoperative the weight of the arm 144 moves it normally to a depending 55 position below the stud 141. The arm 144 has a surface 145 (Fig. 16) adapted to engage a stop 146 formed on the end of an arm 147 rigidly secured to a fixed portion of the frame.

60 The pinion 143 is formed on the end of a stud 148 slidable in a sleeve 149 and having a key-way 150 co-operating with a pin-key 151 mounted in the sleeve, whereby relative angular movement of the pinion and

sleeve is prevented. The sleeve 149 is freely 65 rotatable in a hub 152 formed on the end of the arm 144. On the front end of the sleeve 149 is clamped an arm 153 having a hub 154 formed on the end thereof within which is slidable a spring-pressed plunger 70 155. The rear end of the plunger 155 is reduced in size and is adapted to enter any one of a concentric series of holes 156 formed in the enlarged outer end of the arm 144. By withdrawing the plunger 155 from the 75 holes 156 the arm 153 may be rotated carrying with it the pinion 143, thus moving the arm 144 and its engaging surface 145 around the periphery of the gear 142. The holes 156 in the arm 144 are so spaced that 80 the movement of the plunger 155 from one hole to the next adjacent hole will correspond to an advance of the grinding wheel amounting to one eighth of a thousandth of an inch, corresponding to a reduction of one 85 fourth of a thousandth in the diameter of the work.

25 A spring 156 encircles the stud 148 within the sleeve 149 and maintains the pinion 143 in position to engage the gear 142. The 90 stud 148 is extended beyond the front end of the sleeve 149 and is provided with a handle 158 by which the pinion may be withdrawn when it is desired to secure a more rapid adjustment of the arm 144 relatively 95 to the gear 142.

30 It will now be clear that the arm 144 with its engaging surface 145 is adjustable around the gear 142, but that after the adjustment is secured it moves positively with 100 the gear. When it engages the stop 146 it positively prevents further advance movement of the gear. As the gear 142 when in operation during the final forward movement of the wheel is positively connected 105 through the pinion 140, the gear 120, and the clutch members 129 and 130, to the cross feed shaft 22, such engagement of the surface 145 with the stop 146 positively limits 110 advance movement of the feed screw and consequently of the wheel carriage. After the parts 145 and 146 are thus engaged the gear 27 on the shaft 22 continues to rotate until the operator stops or reverses the feed, such rotation being permitted by the friction drive between the gear 27 and the 115 shaft 22.

35 While we have thus provided a very accurate device for stopping the feed of the grinding wheel it will be evident that the 120 movement of the gear 142 and stop-engaging member 144 is limited to a portion of one revolution, corresponding to a much smaller portion of a revolution of the shaft 22. It is therefore impossible to effect any considerable feed of the wheel carriage after the gear 142 is connected with the shaft 22, under the normal operation of the machine, 125

and we therefore provide means for automatically engaging the clutch members 129 and 130 when the forward feed of the grinding wheel is substantially completed. This 5 engaging means will now be described.

The yoke 136 (Fig. 12) which controls the sliding collar 135 is formed on the end of a lever 160 (Fig. 3) loosely mounted upon the vertical shaft 78 and having an arm 161 extending on the opposite side of said shaft. In the end of the arm 161 there is yieldingly mounted a plunger 162 (Fig. 17) encircled by a spring 163. The plunger 162 is alined with a rod 164 (Figs. 17 and 18) slidably in 10 fixed bearings 165, 166 and 167, and provided at its rear end with rack teeth 168 meshing with a pinion 169 rotatable in a fixed bearing 170 (Fig. 19) and meshing in turn with a gear 171 rotatable in a fixed 15 bearing 172 adjacent the bearing 170. A worm gear 173 is secured to a shaft 174 having a bearing within the hub of the gear 171 and meshes with the feed screw 21. The 20 gears 171 and 173 are provided with coöperating friction surfaces which are forced yieldingly together by a spring 175, as 25 clearly shown in Fig. 19.

With these connections it will be evident that the rack rod 164 will be advanced in 30 timed relation with the wheel carriage until it engages the plunger 163 in the arm 161. Continued forward movement of the rack rod moves the lever 160 and yoke 136 to 35 shift the sliding collar 135 (Fig. 12) thereby by moving the engaging portions of the pawls 133 inward and permitting the spring 124 to force the clutch member 129 toward the clutch member 130, and to enter driving 40 relation therewith as soon as the irregularly spaced teeth of the two clutch members are 45 properly alined, which alinement can occur at one point only in a revolution of the shaft 22. Thereafter the gear 142 and arm 144 will move in unison with the shaft 22 until the stop 146 is engaged, and thereby prevents further rotation of the shaft 22, and the cross feed screw 21.

The spring 163 is of sufficient power to 50 overcome without compression the resistance of the flat springs 137 which hold the pawls 133 in engagement with the keys 123, and the friction between the gears 171 and 173 is materially stronger than the spring 163, so that the relative adjustment of these 55 gears cannot be changed by pressure transmitted through the spring.

When a change is made to work of a larger diameter, it is necessary to advance the rod 164 so that it will engage the plunger 60 162 correspondingly earlier. For this purpose we provide a hand rod 180 (Fig. 17) slidable in a fixed bearing 181 on the frame member 10* and also slidable in a collar 182 secured to the rod 164. The hand rod 180 65 is provided with a knob 183 at its forward

end and with check nuts 184 at its rear end. By grasping the knob 183 the hand rod may be pulled forward, carrying with it the rack rod 164, such movement being possible by overcoming the friction between the 70 gears 171 and 173. When the rod 164 has been positioned to engage the clutch members 129 and 130 at approximately the desired point the final adjustment of the stopping mechanism is obtained by adjusting the 75 arm 144 around the gear 142 by the index mechanism previously described. It will be noted that the hand rod 180 is freely slid- 80 able rearwardly so that accidental pressure thereon will not disturb the adjustment of the rack rod 164 and the gears 171 and 173.

It will also be noted that very accurate adjustment of the point of engagement of the rack rod 164 and plunger 162 is not necessary so long as the clutch member 129 85 is always released for engagement with the member 130 during some part of the same revolution of the cross feed shaft 22.

It will be understood that other well known forms of friction connections can be 90 substituted between the lever 161 and the worm gear 173, it being merely necessary to provide a friction device of some form strong enough to overcome the springs 163 and 137.

We have also provided means for disengaging the clutch members 129 and 130 upon the reversal of the feed mechanism. This provision includes an arm 190 (Figs. 3 and 17) connecting the upper and lower portions 100 of the sleeve 79 and provided with an adjusting screw 191 engaging the arm 161 of the shaft lever 160. As previously described, the sleeve 79 (Fig. 10) carries at its upper end the reverse lever 109 and at its lower end the reverse cam 108. Movement of the reverse lever to the position marked "Back" in Fig. 4 causes the adjusting screw 191 to engage and move the arm 161, overcoming the resistance of the spring 163. The yoke 136 is thus moved to withdraw the collar 135, compressing the spring 124 (Fig. 12) and permitting the pawls 133 to engage the overhanging portions of the keys 123, by which engagement the clutch members 129 115 and 130 are held out of engagement.

The collar 182 on the rack rod 164 is positioned to engage the rear end of the bearing 165 as soon as the rack rod has moved the lever 160 sufficiently to release 120 the pawls 133 and thus permit engagement of the clutch members 129 and 130.

Having described the operation of the several parts in connection with the detailed description thereof, it is thought that 125 an extended statement of the operation of our invention is unnecessary. It will be seen that we have provided for fast, intermediate and slow feed of the wheel carriage and also for reversal of feed at any speed, 130

the feed selection and reversal being at all times under the control of the operator. At the same time, we have provided a mechanism preventing the operator feeding 5 the wheel carriage manually, thereby insuring that the feed shall be at the predetermined rate which is adapted to the particular grinding wheel with which the machine is equipped. The stopping mechanism 10 is so designed that it will operate with extreme positiveness and accuracy and the devices by which this mechanism may be set are exceedingly simple in operation.

In the usual operation of the machine 15 upon rough forgings or castings, it is expected that the operator will advance the wheel at the fast feed until the wheel engages the irregular projections upon the work. He will then shift to the intermediate feed, at which feed the wheel will be advanced until it engages the solid stock of the forging or casting. A shift is then made to slow feed for the normal grinding 20 operation which continues until automatically thrown out by the stopping mechanism. The operator then reverses the feed by the lever 109 and also shifts the feed lever 82 so that he may withdraw the wheel at high speed. The feeding operation is 25 thus fully automatic while at the same time it is always under the control of the operator.

If, after the feed has been automatically thrown out by the stopping mechanism, it is found desirable to grind off a further 30 small amount, the pin 155 on the micrometer feed adjustment may be drawn out against the action of its spring and moved back one or more notches as desired, thus rotating the pinion 143 to move the arm 35 144 backward relative to the stop. The grinding wheel may then be automatically fed forward a further slight amount until the stop 146 is again engaged. It will be observed, however, that this fine adjustment 40 of the feed can be utilized only while the clutch members 129 and 130 are engaged.

Having thus described our invention, it will be evident that changes and modifications can be made therein by those skilled 50 in the art without departing from the spirit and scope of our invention as set forth in the claims, and we do not wish to be otherwise limited to the details herein disclosed, but what we claim is:—

55 1. A cross feed mechanism for grinding machines comprising a wheel carriage, a cross feed shaft having driving connection therewith, automatic means for rotating said feed shaft, and manually-operated devices 60 effective to control said automatic means, said automatic means constituting the sole feeding means for said wheel carriage, and being operable by power only.

65 2. A cross feed mechanism for grinding machines comprising a wheel carriage, au-

tomatic mechanism for feeding said carriage toward and from the work at any one of a plurality of definitely related speeds, and means under the control of the operator to selectively determine the speed and direction of feed, said automatic mechanism constituting the sole feeding means for said wheel carriage, and being operable by power only.

3. A cross feed mechanism for grinding 75 machines comprising a wheel carriage, power-driven means to advance said carriage continuously and uniformly at fast, intermediate and slow feeds, said means comprising gearing having fixed predetermined speed relations, and manually controlled devices for selectively rendering said predetermined feeds effective.

4. A cross feed mechanism for grinding 80 machines comprising a wheel carriage, a cross feed shaft having driving connection therewith, an intermediate shaft, a driving shaft, means including gearing by which the speed relation of said driving shaft to said intermediate shaft may be definitely 85 changed, means including additional gearing by which the speed relation of said intermediate shaft to said cross feed shaft may be definitely changed, and manually-operated devices for controlling said feed changing 90 means.

5. A cross feed mechanism for grinding 95 machines having, in combination, a wheel carriage, a cross feed shaft having driving connection therewith, a driving shaft, speed changing gearing between said driving shaft and said cross feed shaft including a differential gear drive for slow feed, and means to selectively control said gearing manually.

6. A cross feed mechanism for grinding 100 machines having, in combination, a wheel carriage, a cross feed shaft having driving connection therewith, a driving shaft, speed changing gearing between said driving shaft and said cross feed shaft including a differential gear drive for slow and intermediate feed and a direct gear drive for fast feed, and manual means to selectively control the 105 operation of said gearing.

7. In a grinding machine, a cross feed mechanism comprising a cross feed shaft, an intermediate shaft, a driving shaft, a reversible gear drive from said driving shaft to said intermediate shaft, a direct gear drive from said intermediate shaft to said cross feed shaft, an additional differential gear drive between said latter shafts, and manual means effective to control said drives and render the same selectively operative.

8. A cross feed mechanism for grinding 120 machines having, in combination, a wheel carriage, a cross feed shaft having driving connection therewith, a stop, a stop engag-

- ing member, connections between said member and said cross feed shaft including a clutch, and automatic means to engage said clutch as the wheel approaches the finish of its cut. 14. A cross feed mechanism for grinding machines having, in combination, a wheel carriage, a cross feed shaft having driving connection therewith, a stop, a stop engaging member, connections between said member and said cross feed shaft including a clutch, and automatic means to engage said clutch as the wheel approaches the finish of its cut, said means including a clutch-engaging spring, devices normally rendering said spring inoperative, and means to move said devices to release said spring. 70
9. A cross feed mechanism for grinding machines having, in combination, a wheel carriage, a cross feed shaft having driving connection therewith, a stop, a movable stop engaging member, a connection between said member and said cross feed shaft including reduction gearing and a clutch, means to hold said clutch normally out of operation, and automatic means to release said clutch for engagement thereof as the wheel approaches the finish of its cut. 15. A cross feed mechanism for grinding machines having, in combination, a wheel carriage, a cross feed shaft having driving connection therewith, a stop, a stop engaging member, connections between said member and said cross feed shaft including a clutch, and means to engage said clutch automatically as the wheel approaches the finish of its cut, said means including a clutch-engaging spring, devices normally rendering said spring inoperative, and means to move said devices to release said spring. 75
10. A cross feed mechanism for grinding machines having, in combination, a wheel carriage, a cross feed shaft having driving connection therewith, feeding mechanism including a friction drive for said cross feed shaft, a stop, a stop engaging member, and means to positively connect said member to said cross feed shaft, said friction drive permitting the stopping of said shaft upon engagement of said member and stop while said feeding mechanism continues in motion. 16. A cross feed mechanism for grinding machines having, in combination, a wheel carriage, a cross feed shaft having driving connection therewith, a stop, a stop engaging member, connections between said member and said cross feed shaft including a clutch, and automatic means to engage said clutch as the wheel approaches the finish of its cut, said means including a yielding element permitting manual disengagement of said clutch without changing the adjustment of said automatic engaging device. 80
20. A cross feed mechanism for grinding machines having, in combination, a wheel carriage, a cross feed shaft having driving connection therewith, feeding mechanism including a friction drive for said cross feed shaft, a stop, a stop engaging member, and means to positively connect said member to said cross feed shaft, said friction drive permitting the stopping of said shaft upon engagement of said member and stop while said feeding mechanism continues in motion. 85
25. A cross feed mechanism for grinding machines having, in combination, a wheel carriage, a cross feed shaft having driving connection therewith, feeding mechanism including a friction drive for said cross feed shaft, a stop, a stop engaging member, and means to positively connect said member to said cross feed shaft, said friction drive permitting the stopping of said shaft upon engagement of said member and stop while said feeding mechanism continues in motion. 90
11. A cross feed mechanism for grinding machines comprising a wheel carriage, a cross feed screw for said carriage, a friction drive for said feed screw, a rotatable stopping member, a fixed stop positioned for engagement by said member, and automatically controlled means for positively connecting said stopping member with said feed screw, said stopping member upon engagement with said stop after a partial revolution of said member positively locking the feed screw against further advance movement. 17. A cross feed mechanism for grinding machines having, in combination, a wheel carriage, a cross feed shaft having driving connection therewith, a stop, a stop engaging member, connections between said member and said cross feed shaft including a clutch, and automatic means to engage said clutch as the wheel approaches the finish of its cut, said means including a friction connection whereby adjustment may be readily made, and a spring plunger permitting manual disengagement of said clutch without disturbing the adjustment of said friction connection. 100
30. A cross feed mechanism for grinding machines comprising a wheel carriage, a cross feed screw for said carriage, a friction drive for said feed screw, a rotatable stopping member, a fixed stop positioned for engagement by said member, and automatically controlled means for positively connecting said stopping member with said feed screw, said stopping member upon engagement with said stop after a partial revolution of said member positively locking the feed screw against further advance movement. 105
35. A cross feed mechanism for grinding machines having, in combination, a wheel carriage, a cross feed shaft having driving connection therewith, a stop, a stop engaging member, connections between said member and said cross feed shaft including a clutch, and automatic means to engage said clutch as the wheel approaches the finish of its cut, said means including a yielding element permitting manual disengagement of said clutch without changing the adjustment of said automatic engaging device. 110
40. A cross feed mechanism for grinding machines having, in combination, a wheel carriage, a cross feed shaft having driving connection therewith, a stop, a stop engaging member, connections between said member and said cross feed shaft including a clutch, and automatic means to engage said clutch as the wheel approaches the finish of its cut, said means including a friction connection whereby adjustment may be readily made, and a spring plunger permitting manual disengagement of said clutch without disturbing the adjustment of said friction connection. 115
45. A cross feed mechanism for grinding machines having, in combination, a wheel carriage, a cross feed shaft having driving connection therewith, a stop, a stop engaging member, connections between said member and said cross feed shaft including a clutch, and automatic means to engage said clutch as the wheel approaches the finish of its cut, said means including a friction connection whereby adjustment may be readily made, and a spring plunger permitting manual disengagement of said clutch without disturbing the adjustment of said friction connection. 120
50. A cross feed mechanism for grinding machines having, in combination, a wheel carriage, a cross feed shaft having driving connection therewith, a stop, a stop engaging member, connections between said member and said cross feed shaft including a clutch, and automatic means to engage said clutch as the wheel approaches the finish of its cut, said means including a friction connection whereby adjustment may be readily made, and a spring plunger permitting manual disengagement of said clutch without disturbing the adjustment of said friction connection. 125
55. A cross feed mechanism for grinding machines having, in combination, a wheel carriage, a cross feed shaft having driving connection therewith, a stop, a stop engaging member, connections between said member and said cross feed shaft including a clutch, and automatic means to engage said clutch as the wheel approaches the finish of its cut, and manual means to disengage said clutch. 130
60. A cross feed mechanism for grinding machines having, in combination, a wheel carriage, a cross feed shaft having driving connection therewith, a stop, a stop engaging member, a connection between said member and said cross feed shaft including reduction gearing and a clutch capable of engagement at one point only of a revolution, and automatic means to engage said clutch as the grinding wheel approaches the finish of its cut. 65

clutch simultaneously with the reversal of the feed.

19. A cross feed mechanism for grinding machines having, in combination, a wheel carriage, a cross feed shaft having driving connection therewith, a fixed stop, a movable stop engaging member, a connection between said member and said cross feed shaft including a clutch, means to hold said clutch normally out of operation, automatic means to release said clutch for engagement thereof as the wheel approaches the finish of its cut, said means comprising a friction-driven actuating member, and manual means for overcoming the friction and advancing said member to adjust said releasing means for work of greater diameter.

20. In a grinding machine, a cross feed mechanism, a driving shaft, two separate devices for establishing predetermined speed relations between said shaft and mechanism, and a single hand-operated cam shaft controlling said two devices.

21. In a grinding machine, a cross feed mechanism including two separate speed changing devices, a hand-operated shaft, and two separate cams on said shaft controlling said two speed changing devices, each cam having a dwell portion and being inoperative while the other cam is operative, whereby one speed changing device will remain unchanged in condition while the other device is being thrown into or out of operation.

22. In a grinding machine, a cross feed mechanism, a driving shaft, two separate devices for establishing predetermined speed relations between said shaft and mechanism, a hand-operated cam shaft controlling said two devices, a reversing mechanism, and a second hand-operated element concentric with said cam shaft for controlling said reversing mechanism.

23. A cross feed mechanism for grinding machines comprising a wheel carriage, a grinding wheel thereon, a support to position the work adjacent said wheel for grinding, and exclusively automatically actuated means to move said carriage and work relative to each other to feed the wheel into the work during a grinding operation.

24. A cross feed mechanism for grinding machines comprising a wheel carriage and a grinding wheel thereon, a support to position the work adjacent said wheel, mechanism to move said carriage and work relatively toward and from each other, a power shaft, and driving connections between said shaft and said mechanism, said mechanism, said shaft and said connections constituting the sole feeding means and producing a continuous mechanical feeding action.

25. A cross feed mechanism for grinding machines comprising a wheel carriage, a grinding wheel thereon, a support to posi-

tion the work adjacent the wheel, mechanically operated means to feed said carriage relative to the work at a uniform, constant rate to insure even grinding, and manually operated means effective to control the automatic means to change the rate without affecting the uniformity of the grinding operation.

26. A cross feed mechanism for grinding machines comprising a wheel carriage and a grinding wheel thereon, a support to position the work adjacent said wheel, a power shaft, automatically operated means continuously driven from said shaft to move said carriage and work relative to each other to feed the wheel into the work at a constant, uniform rate of cutting during a grinding operation, and manually operated means for controlling the rate and direction of the cross feed operation but preventing manual feeding at will to produce a non-uniform grinding action.

27. A cross feed mechanism for grinding machines having, in combination, a wheel carriage, a cross feed shaft having driving connection therewith to move the carriage, driving mechanism, two frictionally engaged relatively adjustable members actuated by said driving mechanism, and means controlled by one of said members to stop the carriage at a predetermined point depending on the adjusted relative positions of said members.

28. A cross feed mechanism for grinding machines having, in combination, a wheel carriage, a cross feed shaft having driving connection therewith to move the carriage, a friction drive actuated by said shaft, means controlled by said friction drive to stop the carriage at a predetermined point, and means to adjust the relative positions of the members of said drive to vary the point of stoppage.

29. A cross feed mechanism for grinding machines comprising a wheel carriage, a grinding wheel rotatably mounted thereon, a support to position the work adjacent said wheel, and automatically actuated means to move said carriage and work relative to each other whereby the work and wheel are moved toward each other during a grinding operation at a continuous uniform and predetermined rate.

30. A cross feed mechanism for grinding machines having, in combination, a wheel carriage, a cross feed shaft having driving connection therewith, a stop, a stop engaging member, connections between said member and said cross feed shaft and automatic means effective as the wheel approaches the finish of its cut to engage said connections and thereby move said member against said stop.

31. A cross feed mechanism for grinding machines having, in combination, a wheel

carriage, a cross feed shaft having driving connection therewith, a fixed stop, a stop engaging member, and means operating automatically as the grinding wheel approaches the finish of its cut to form a positive connection between the cross feed shaft and said stop engaging member, said connection being also effective to increase

the movement of said member relative to the movement of said shaft. ¹⁰

In testimony whereof we have hereunto affixed our signatures.
